(57) **CLAIM**

The ornamental design for a rod packaging box, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of the rod packaging box showing my new invention;

FIG. 2 is a right side perspective view thereof;

FIG. 3 is a left side perspective view thereof;

FIG. 4 is a top view thereof;

FIG. 5 is a rear perspective view thereof;

FIG. 6 is a bottom perspective view thereof; and,

FIG. 7 is a bottom view thereof.

1 Claim, 7 Drawing Sheets
(7 of 7 Drawing Sheet(s) Filed in Color)
